United States Patent Office.

JOHN H. GOODFELLOW, OF TROY, NEW YORK, ASSIGNOR TO HIMSELF AND R. S. GOODFELLOW, OF SAME PLACE.

Letters Patent No. 90,524, dated May 25, 1869.

COAL-STOVE.

The Schedule referred to in these Letters Patent and making part of the same.

To all whom it may concern:

Be it known that I, JOHN H. GOODFELLOW, of Troy, Rensselaer county, New York, have invented a new and useful Improvement in Parlor-Stoves; and I do hereby declare that the following is a full, clear, and exact description thereof, which will enable others skilled in the art to make and use the same, reference being had to the accompanying drawing, forming part of this specification.

The figure is a detail sectional view of my improved stove.

My invention has for its object to furnish an improved side-draught stove, which shall be so constructed and arranged that it may be used with equal facility, and with equal advantage, for burning bituminous and anthracite coals; and

It consists in the construction and combination of various parts of the stove, as hereinafter more fully described.

A is the interior cylinder or fire-box of the stove, the sides of which are perforated with holes, to allow the products of combustion to pass through the sides of the fire-box.

The fire-box is lined with fire-brick, B, or other suitable fire-proof material, which is perforated with holes to correspond with the holes through the cylinder, or case A.

The upper part of the cylinder A flares or inclines outward, so that it may come in contact with the outer case, or cylinder C, thus forming a chamber, or flue D, all around the fire-box A, into which the products of combustion pass.

E is a plate, placed at the lower edge of the forward part of the cylinder A, and extending about half way round, which forms the bottom of the forward part of the flue D.

At the rear part of the stove the flue D extends down to the plate F, which forms the bottom of the rear part of the flue D and the bottom of the flue G.

The plate F is placed at or near the middle of the base H.

The forward ends of the plate F, at each side of the entrance to the ash-pit, are cut away, to form openings for the products of combustion to pass down into the flue I, between the plate F and the bottom of the stove, through which fine the said products of combustion pass to the egress-flue J, at the rear part of the stove, through which they escape to the chimney.

The air to supply combustion is introduced through an opening in the top of the stove, which opening should be closed with a damper, K, so that the draught may be regulated at will.

L is a short pipe, the upper end of which is attached to the top plate of the stove, around the draught-opening in the said top plate.

The pipe L terminates near the concave or dish-

shaped plate M, which is connected with and supported from the inverted cone N, in such a way as to leave a narrow space or opening between the edges of said plates M and N, as shown in the figure.

The upper edge of the inverted conical plate N extends out a little further than the dished plate M, so as to come in contact with and be connected to the case, or cylinder C.

The lower part of the conical plate N is perforated with numerous small holes, as shown in the figure, so that the air may be divided up as it is introduced into the chamber or space above the fire-box.

By this arrangement the air will be heated while being introduced into the fire-chamber, and will be divided or separated into numerous small streams, so that the combustion of the fuel may be more general and uniform through all parts of the fire-box.

By the use of the plate M, it is designed to prevent the cold air entering through pipe L from passing directly downward through the perforated conical plate N, and, by so doing, to insure that said air shall become more or less heated by coming in contact with the plate M, the sides of the stove, and the imperforate outer portion of the conical plate.

The plates M and N may be secured at a point nearer or further from the damper K, or top of the stove, according to the amount of heating-surface, or the degree of heat to which it may be deemed necessary to expose the air before allowing it to reach the fire.

In any case, the pipe L can be adjusted as to length, corresponding to the location of the plates M and N.

I claim as new, and desire to secure by Letters Patent—

1. The air-chamber, formed in the upper part of the stove, by the combination of the perforated inverted conical plate N, dished plate M, and pipe L, with each other, and with the top and sides of the case C, substantially as herein shown and described, and for the purpose set forth.

2. The plate E, in combination with the outer case C, inner perforated case A, plate F, and base H of the stove, substantially as herein shown and described, to produce the arrangement of the flues D G I, herein set forth.

3. The fire-box A, having the perforations *a* in its side, and lined with the fire-brick B, perforated with holes corresponding with those in the fire-box, substantially as and for the purpose specified.

The above specification of my invention signed by me, this 8th day of March, 1869.

JOHN H. GOODFELLOW.
